UNITED STATES PATENT OFFICE.

RUFUS E. RAMSDELL, OF NEWTON, MASSACHUSETTS.

POCKET IGNITING DEVICE.

1,027,900.

Specification of Letters Patent.

Patented May 28, 1912.

Application filed August 19, 1911. Serial No. 644,931.

To all whom it may concern:

Be it known that I, RUFUS E. RAMSDELL, a citizen of the United States, residing at Newton, in the county of Middlesex and State of Massachusetts, have invented new and useful Improvements in Pocket Igniting Devices, of which the following is a specification.

This invention relates to improvements in pocket lighters or igniters of that class in which a spark-producing element is arranged adjacent to a mass of absorbent material saturated with some volatile inflammable liquid such as gasolene, so that if the spark-producing element be struck or rubbed by a suitable substance a spark will be produced to light the vapor from the gasolene.

The object of my present invention is to provide a simple, convenient and easily operated device of the class referred to having provision for adjusting a spark-producing element as it wears away.

To this end, my invention consists in the novel features of construction and in the combination and arrangement of parts set forth in the following specification and particularly pointed out in the claims.

Referring to the drawings: Figure 1 is a central sectional view of an igniting device embodying my invention with the cap in the position which it occupies when the igniter is placed in the pocket and is not in use for lighting purposes. Fig. 2 is a sectional view taken on line 2-2 of Fig. 1. Fig. 3 is a sectional view taken on line 3-3 of Fig. 1. Fig. 4 is an enlarged detail sectional view taken on line 4-4 of Fig. 1. Fig. 5 is a central sectional view of a modification of my invention. Fig. 6 is a sectional view taken on line 6-6 of Fig. 5. Fig. 7 is a sectional view taken on line 7-7 of Fig. 5. Fig. 8 is a sectional view taken on line 8-8 of Fig. 5. Fig. 9 is a central sectional view of a second modification of my invention.

Like numerals refer to like parts throughout the several views of the drawings.

In the drawings, referring to the form of the invention which is illustrated in Figs. 1 to 4, inclusive, the numeral 10 designates generally a casing consisting of two parts 11 and 12 coaxially arranged to rotate one upon the other, said casing having a closed end 13 and an open end 14. The two parts 11 and 12 are held against longitudinal dis-

placement by any suitable means such, for example, by rolling the circumferential wall of both parts inwardly to form interengaging corrugations 15 and 16 on the parts 11 and 12, respectively. Located within the casing 10 is a spark-producing element 17 formed of well known alloy for this purpose and within the casing there is also provided a body of suitable absorbent material 18 as, for example, absorbent cotton, which may be saturated with gasolene or other inflammable liquid which will vaporize readily. The igniting element 17 is provided with suitable means of adjustment 60 whereby the same may be adjusted at will to vary its position with respect to the open end 14 of the casing 10 and preferably this adjustment is accomplished by relative rotation of the two parts 11 and 12 of the 65 casing in the following manner. Located within and secured to the part 11 is a nut 19 having screw-threaded engagement with a screw 20 both coaxially arranged with respect to the casing 10. The spark-producing element 17, it will be observed, is located at one side of the axis of the casing 10 and of the screw and nut 19 and 20 and in addition, said element is disposed at an 70 angle to said axis. The upper end of the 75 element 17 is guided by a guide 21 secured to the interior of the part 12 and said guide and said spark-producing element are polygonal or some other suitable cross sectional shape so as to prevent the spark-producing element from rotating within the 80 guide. In the present instance, the spark-producing element is square in cross section and the guide 21 is suitably shaped, as 85 shown in Fig. 3. The spark-producing element 17 is connected to the screw 20 by suitable means whereby when a relative 90 rotative movement is imparted to the parts 11 and 12 the spark producing element rotates the screw 20 in the nut 19 and consequently 95 100 the spark-producing element is moved longitudinally by the guide 21 and for this purpose the spark-producing element is connected to the screw by a flexible coupling 105 consisting of a helical spring 22 screwed onto the screw 20 and interengaging with the threads thereof, as shown somewhat enlarged in Fig. 4, while the upper portion of the spring encircles a shaft 23 which may be provided with suitable corrugations or 110 indentations 24 to receive the convolutions of the spring 22, while, in turn, said shaft

is connected to the igniting element by a similar flexible coupling 25 attached to said shaft and to said spark-producing element in a similar manner. Thus it will be seen that while the spark-producing element 17 bears an angular relation to the screw 20 and although the angle increases as the screw is moved upwardly to feed the spark-producing element upwardly, the flexible coupling 22 and the flexible coupling 25 will provide for the proper relative motions between the parts in a simple and inexpensive way. The casing may be provided with any suitable cap as, for example, a cap 26 having a groove 27 in which is located a scratching element 28 which may consist of a piece of file, although it will be distinctly understood that my present invention is not limited to a cap and scratching element of this particular character. When it is desired to produce a light by means of the device, the cap is moved and inverted with the scratching element 28 upon the igniting element 17, after which the scratching element is rubbed across the end of the igniting element toward the right, thus producing a spark which will ignite the vapor from the open end of the casing 10.

Referring now to the form of my invention which is illustrated in Figs. 5 to 8, inclusive; the numeral 29 designates generally a casing consisting of two parts 30 and 31 coaxially arranged and mounted to rotate with respect to each other, said parts being held against relative longitudinal displacement by interengaging corrugations 32 and 33 similar to those hereinbefore described. Located within the casing 29 is an igniting element 34 consisting of a suitable alloy well known to those skilled in the art for this purpose, said element being located at one side of the median axial line of the parts 30 and 31 and being guided by a suitable guide 35 which, in the present instance, consists of a tube 45 which is circular in its upper portion, as shown in Fig. 7, and is cut away therebelow so as to be semi-circular, as shown in Fig. 8, for a purpose which will presently appear. Located within and secured to the part 30 is 50 a nut 36 having screw-threaded engagement with a screw 37 coaxially arranged with respect to the casing 29 and having formed thereon or secured thereto a crank-arm 38 to which the igniting element 34 is attached in any suitable manner, whereby when a relative rotation is imparted to the two parts 30 and 31 of the casing 29 the screw 37 is rotated within the nut 36 and consequently a longitudinal feeding movement is imparted 55 to the igniting element 34. Thus it will be evident that by grasping the two parts of the casing and turning the same in opposite directions the spark-producing element may be fed out of the open end of the casing as 60 said element wears away when in use. The

casing may be provided with a suitable cap 39 carrying a suitable scratching element 40 which will be utilized to strike a spark in the same manner in which the spark is produced by the first form of my invention 70 hereinbefore described.

Referring now to Fig. 9, wherein I have shown a second modified form of my invention, the numeral 14 designates generally a casing formed in two parts 42 and 43 coaxially arranged to rotate one upon the other, said casing having a closed end 44 and an open end 45. The two parts 42 and 43 are held against longitudinal displacement by any suitable means such, for example, as by 80 means of interengaging corrugations 45 and 46. Preferably, the part 42 is extended laterally somewhat to form a flange 47 which may be round, as shown, so that it may readily be turned with the fingers. Located within the casing 41 is a spark producing element 48 and within said casing there is also provided a body of suitable absorbent material 49 which, of course, will be saturated with gasoline or other suitable liquid, the same as the forms hereinbefore described. The igniting element 48 is provided with a means of adjustment consisting of a nut 50 secured to the part 42 and having screw-threaded engagement with a rod 95 51 whose screw-threaded portion is coaxially arranged with the casing 41, said rod being provided with an offset portion 52 which is guided by a guide 53 secured to the part 43 of the casing. To the upper end of the offset portion 52 the igniting element 48 is secured by any suitable means as, for example, a coupling 54 consisting of a helical spring. In this form of my invention also, the igniting element as it wears away is adjusted by 105 rotating the two parts of the casing with respect to each other. As a means for preventing the offset portion 52 from turning in the guide 53 as the two parts of the casing are rotated with respect to each other, 110 said offset portion is made square and the guide correspondingly square, the same as in the form shown in Figs. 1 and 3.

Having thus described my invention, what I claim and desire by Letters Patent to secure is:

1. An igniter having, in combination, a casing consisting of two coaxially arranged parts mounted to turn one upon the other, said casing having an orifice; a spark-producing element mounted in said casing adjacent to said orifice, means operated by the relative rotation of said parts for adjusting said spark-producing element with respect to said orifice, and a mass of absorbent material in said casing. 120

2. An igniter having, in combination, a casing consisting of two coaxially arranged parts mounted to turn one upon the other, said casing having an orifice, a spark-pro- 125

- ducing element mounted in said casing adjacent to said orifice, a screw and nut operated by the relative rotation of said parts for adjusting said spark-producing element with respect to said orifice, and a mass of absorbent material in said casing.
3. An igniter having, in combination, a casing consisting of two coaxially arranged parts mounted to turn one upon the other, said casing having an orifice, a spark-producing element mounted to revolve with one of said parts about the axis of said parts, a screw and nut arranged coaxially with said parts, said nut being secured to the other of said parts, and said screw being connected to said spark-producing element whereby the relative rotation of said parts adjusts said spark-producing element longitudinally of said axis, and a mass of absorbent material in said casing.
4. An igniter having, in combination, a casing consisting of two coaxially arranged parts mounted to turn one upon the other, said casing having an orifice, a spark-producing element located at one side of the axis of said parts, a guide for said spark-producing element, said guide being secured to one of said parts, and a screw and nut arranged coaxially with said parts, said nut being secured to the other of said parts and said screw being connected to said spark-producing element whereby the relative rotation of said parts adjusts said spark-producing element longitudinally of said axis, and a mass of absorbent material in said casing.
5. An igniter having, in combination, a casing consisting of two coaxially arranged parts mounted to turn one upon the other,
- 5 10 15 20 25 30 35
- said casing having an orifice, a spark-producing element mounted to revolve with one of said parts about the axis of said parts, a screw and nut arranged coaxially with said parts, said nut being secured to one of said parts, and the other of said parts being provided with means for revolving said spark-producing element about said axis and holding said element against rotation upon its own axis, a flexible angular driving connection between said screw and said spark-producing element, and a mass of absorbent material in said casing.
6. An igniter having, in combination, a casing consisting of two coaxially arranged parts mounted to turn one upon the other, said casing having an orifice, a spark-producing element located at one side of the axis of said parts and disposed in inclined position with respect to said axis, a screw and a nut arranged coaxially with said parts, said nut being secured to one of said parts, and the other of said parts being provided with means for revolving said spark-producing element about said axis and holding said element against rotation upon its own axis, a helical spring forming a flexible angular driving connection between said screw and said spark-producing element, and a mass of absorbent material in said casing.
- In testimony whereof I have hereunto set my hand in presence of two subscribing witnesses.
